UNITED STATES PATENT OFFICE

147,002

DESIGN FOR A WATCH SUPPORT

John Elisha Bartlett, Los Angeles, Calif.

Application August 5, 1946, Serial No. 132,300

Term of patent 7 years

(Cl. D42—9)

To all whom it may concern:

Be it known that I, John Elisha Bartlett, a citizen of the United States of America, and a resident of Los Angeles, in the county of Los Angeles, State of California, have invented a new, original, and ornamental Design for a Watch Support, of which the following is a specification, reference being had to the accompanying drawing, forming a part thereof.

In the drawing:

Figure 1 is a front elevational view of a watch support, showing my new design.

Figure 2 is a top-plan view of the watch support; and,

Figure 3 is a side-elevational view thereof.

I claim:

The ornamental design for a watch support, as shown.

JOHN ELISHA BARTLETT.
